UNITED STATES PATENT OFFICE.

WALTER SCOTT, OF PLAINFIELD, NEW JERSEY.

PRINTING AND FOLDING MACHINE.

SPECIFICATION forming part of Letters Patent No. 753,169, dated February 23, 1904.

Application filed May 14, 1901. Serial No. 60,196. (No model.)

To all whom it may concern:

Be it known that I, WALTER SCOTT, a citizen of the United States, and a resident of Plainfield, in the county of Union and State of New Jersey, have invented a certain new and useful Improvement in Printing and Folding Machines, of which the following is a specification.

The present invention relates to modern printing and folding machines of the class wherein one (or more) webs of paper are perfected and are taken to a folding machine or machines to be folded longitudinally and then cut into lengths for delivery with or without further folding, though in so far as the main features of my invention are concerned the paper or webs may be manipulated in other or known ways, as by using the longitudinal folder to associate web-sections or narrow webs or by having the transverse cutting precede the folding.

This invention is intended more especially for use in locations where the walls of the building or the positions of supports or other machinery prevent the straight run of the web through both printing and folding mechanisms.

In its general organization the present invention consists in perfecting printing mechanism delivering its web (or webs) in or traveling in one plane, a suitable folding mechanism arranged so that the general direction of travel of the paper therethrough is at an angle to the first-named direction, said angle being other than a right angle, and means interposed between the printing and folding mechanisms for guiding the web from one to the other of said paths of travel. The delivery may be located to suit the requirements of the particular case, though, generally speaking, it is preferable to locate it on that side of the folding mechanism left vacant by the angle between the press and folder.

The preferred form of the invention is illustrated in the accompanying drawings, forming part of this specification, in which—

Figure 1 is a diagrammatic side elevation of a printing and folding machine in which the invention is embodied, and Fig. 2 is a partial plan of the same.

In the drawings I have omitted all driving mechanism, as the same may be of any character suited to the particular case; also, the common framework in which the parts are mounted in appropriate manner is omitted; 55 also, the inking and other mechanisms the showing of which is not essential to an understanding of the present invention are omitted from the drawings for the sake of clearness.

The driving mechanisms hereinafter referred to are such as a mechanic skilled in the art can easily supply.

In illustrating my invention I have elected to show three web-perfected printing-presses, A B C, arranged one above another, and a longitudinal folder F, set at such an angle to each other as that the courses of the paper in passing through the presses lie in one vertical plane, as it were, while the course of the paper in passing to the folder is at an angle other than 70 a right angle to the said vertical plane. Intermediate the printing and the folding mechanisms I arrange the means for guiding the paper from one to the other of said vertical planes.

The reference D marks the distributing cylinders of a suitable inking apparatus.

The web a receives impressions thereon from the first-impression and plate cylinders i' p' on its upper side and impression on its under side from the second-impression and plate cylinders i² p² of the press A as the web passes therethrough. The webs b c receive impressions on their under sides from the first-impression and plate cylinders i' p' and on 85 their upper sides from the second-impression and plate cylinders i² p² of their respective presses B and C. From the presses these webs are led about suitable guide-rollers d. The web a passes between a roller e and a 90 paste-applying disk f and receives when it is so desired a line of paste along its upper side. Then the web a passes about an angle-bar g backward to and about a lower guide-roller h and over a roller k at the top of the folder F. 95 In passing from the roller e about the bar g to the lower roller h the direction of travel of the web is changed from one plane to another, forming an acute angle with the first plane, the rollers e and h being set at an angle to 100

each other and the bar *g* being at an angle to each of said rollers. The roller *e* is parallel with the cylinders of the presses, and the rollers *h* are parallel with the roller *k*. The bar 5 *g* is suitably grooved to permit the line of paste on the web *a* to pass it without touching. The web *b* passes from a roller *d* to and between a roller *e* and a paste-applying disk *f*, where it may receive a line of paste along 10 it, as in the case of the web *a*. From the roller *e* the web *b* is led around a roller *m*, parallel with the cylinders of the presses, and which is grooved circumferentially to prevent the paste from touching it, and to an angle-bar *n* and thence about rollers *h* to the roller *k*. The roller *m* is journaled in arms *o* of a shaft *p*, which is journaled in the framework of the machine, whereby the position of the roller *m* may be varied in order to secure 15 register with the web *a*. Suitable gearing (not shown) may be employed to drive the roller *m* in all positions thereof at such speed as will cause the said roller, acting in conjunction with the rollers or friction-disks *q*, to keep the web *b* taut and to feed it forward 20 to the angle-bar *n* at the speed at which the web is delivered by the press *B*. The disks *q* are mounted on a shaft *s*, which is carried by arms *t* from the shaft *p*, so that the rollers 25 or disks *q* and the roller *m* have the same external center of motion. From the bar *n* the web *b* passes to a roller *h*, where it is associated with the web *a* and is caused to adhere thereto whenever paste has been applied to 30 the upper side of the web *a*. The web *c* passes from a roller *d* to and about a roller *u*, thence to and about an angle-bar *v*, to and 35 about a roller *h*, and to the roller *k*, where it is associated with the webs *a b* and is caused to adhere to the latter whenever paste has 40 been applied thereto. A set of tapes *w*, running on rollers or pulleys *x y*, sustains the web *c* between the rollers *d* and *u*, the tapes being run at such a speed as will cause them 45 and the roller *u* to keep the web taut and deliver it to the angle-bar *v* at the same speed it has when leaving the press *C*. The pulleys *y* are supported by arms from a journaled shaft *z*, whereby the tapes may be kept 50 taut by proper adjustment of the shaft and arms, as will be understood by those skilled in the art.

The rollers *e*, *h*, and *k* and also the tapes *w*, and rollers *m* and *u* are driven preferably at 55 a speed slightly greater than the speed of the cylinders of the presses, whereby the webs are kept taut and drawn about the angle-bars, and I remark that the register of the webs may be secured in any known manner and that all the 60 bars and rollers about which the paste-carrying sides of the web pass are grooved to permit the paste to pass them without touching. I also remark that the webs after being folded by the longitudinal former or internal guide 65 and the drawing or laying rolls *l* may be fur-

ther folded and cut transversely prior to their delivery as separate cuts or copies and that the delivery may be located with respect to the folder *F* as may be most convenient, the forms on the plate-cylinders being arranged 70 accordingly; but in general it is desirable that the delivery take place on that side of the folder *F* where the folder would be placed in part were the webs to run straight through both printing and folding mechanisms without being turned from one to another plane or run in two directions forming an acute angle with each other, as this economizes space and the delivery does not project so far beyond the general outline of the machine, and 75 it is obvious that supporting-tapes may be used for all of the webs as well as for the web *c*; also, that one or more of the printing-presses may be used, the remainder being silenced for the time being, and the printed web 80 or webs be associated and folded, cut, and delivered.

It is remarked that each web before being associated with any other web is drawn around the bar placed at an angle to the course of the 85 web, so that each web is smoothed out by its said bar before any association occurs, thus avoiding folds or wrinkles, with possible tears, in the folded products delivered by the machine.

It will be observed that the web *a* after leaving the printing-press passes to the bar *g* and backward to a roller *h* and that the webs *b c* first pass over rollers *m u* and then to the bars *n v*. This change is necessary, since it 90 is desirable that the sides of the webs first printed should come in contact with the turning-bars, the surplus ink on that side having been taken off by the contact with the second-impression-cylinder blanket during the taking 95 of the impressions on the other side and the web *a* going into its press differently from the way the webs *b c* go into their respective presses.

The reference *E* designates the angles formed 100 by the sides of the framework wherein the presses and the folding mechanism are severally mounted.

What is claimed as new is—

1. The combination with a web-perfecting 115 printing mechanism through which the web-path lies in one plane, of folding mechanism into which the paper passes by a path in a plane forming an acute angle with the first-named plane, and means interposed between 120 said printing and folding mechanisms for reversing the direction of travel of the paper and also changing the course thereof from one to the other of said planes, substantially as described.

2. The combination with a plurality of web-perfecting printing mechanisms through which the web-path lies in one plane, of folding mechanism over a roller of which the paper passes into said mechanism by a path 130

in a plane forming an acute angle with the first-named plane, reversing-rollers parallel with the cylinders of the printing mechanism, guide-rollers parallel with said roller of the folding mechanism, and angle-bars interposed between the reversing and the guide rollers, substantially as described.

3. The combination with web-perfecting printing mechanism through which the web-path lies in one plane, of a longitudinal folder into which the web passes by a path in a plane forming an acute angle with the first-named plane, and means interposed between said printing mechanism and folder for reversing the direction of travel of the web and also changing the course thereof from one to the other of said planes, substantially as described.

4. The combination with web-perfecting printing mechanism through which the web-path lies in one plane, of a longitudinal folder into which the web passes by a path lying in a plane forming an acute angle with the first-named plane, reversing-rollers parallel with the cylinders of the printing mechanism, guide-rollers parallel with a roller at the top of the folder, and angle-bars interposed between the reversing and the guide rollers.

5. The combination with a web-perfecting press whose cylinders are parallel with each other and through which the web-path lies in one plane, of a folding mechanism into which the paper passes by a path in a plane forming an acute angle with the first-named plane, a roller of the folding mechanism forming with the cylinders of the said press an acute angle the same as the first-named angle, and an angle-bar placed at an acute angle with both said roller and said cylinders, substantially as described.

6. The combination with a web-perfecting printing-press through which the web-path lies in one plane, of a folding mechanism into which the paper passes by a path in a plane forming an acute angle with the first-named plane, a reversing-roller parallel with the cylinders of said press, a guide-roller parallel with a roller of the folding mechanism, and an angle-bar interposed between the reversing and the guide rollers, substantially as described.

7. The combination with a web-perfecting printing-press through which the web passes in one plane, of a folding mechanism placed at an obtuse angle to the printing-press, a guide-roller parallel with a roller of the folding mechanism, a guide-roller parallel with the cylinders of the press, and an angle-bar placed at an angle with both of said guide-rollers, whereby the course of the web is changed from its path through the printing-press to its path through the folding mechanism, substantially as described.

8. The combination with a plurality of web-perfecting printing-presses arranged one above another, of a folding mechanism placed

at an obtuse angle to the web-path through said presses, guide-rollers parallel with the cylinders of said presses, guide-rollers parallel with a roller at the folding mechanism, and bars placed at an angle with both sets of guide-rollers, whereby the web-path is changed from one to another plane, substantially as described.

9. The combination of a web-perfecting printing-press through which the web-path lies in one plane, a longitudinal folding mechanism into which the paper passes by a path at an angle other than a right angle to said web-path, a guide-roller placed at an acute angle to the cylinders of said press, and a turning-bar located between said press and said roller and placed at an angle to said cylinders and said roller, substantially as described.

10. The combination with a web-perfecting printing-press through which the web-path lies in one plane, a longitudinal folder into which the paper passes by a path forming an angle other than a right angle with said web-path, a roller at an acute angle with the cylinders of said press and at right angles to the folding-rollers of the longitudinal folder, and a turning-bar located between the press and the folder and placed at angles with both said roller and the cylinders of the press, substantially as described.

11. The combination with a web-perfecting printing-press through which the web-path lies in one plane, a longitudinal folder into which the paper passes by a path forming other than a right angle with the said web-path, a guide-roller at an acute angle to the cylinders of said press and at right angles to the folding-rollers of the said folder, and an angle-bar located between the press and the said guide-roller, with means for guiding the web to said bar in such wise that the side first printed comes into contact with said bar, substantially as described.

12. The combination with a web-perfecting printing-press through which the web-path passes in one plane, of a folding mechanism into which the paper passes by a path forming an acute angle with said web-path, a reversing-roller parallel with the cylinders of said press, a guide-roller parallel with a roller of the folding mechanism, an angle-bar interposed between the reversing and the guide rollers at an angle to both, and means for feeding the web to the bar at the speed at which it comes from the press, whereby the strain on the web is not drawn by the folding machine around the bar but from the bar only, substantially as described.

13. The combination with a web-perfecting printing-press through which the web-path lies in one plane, of a folding mechanism into which the paper passes by a path in a plane forming an acute angle with the first-named plane, an adjustable reversing and registering

- roller parallel with the cylinders of the said press, a guide-roller parallel with a roller at the folding mechanism, an angle-bar interposed between the reversing and the guide rollers, and friction-rollers coacting with the reversing-roller so that as the registering-roller is adjusted the friction-rollers will remain in the same relation thereto, substantially as described.
14. In a printing and folding machine, the combination of means for diverting a web from a path in one vertical plane into another path in a vertical plane at an acute angle to the first, with printing mechanism delivering a web into the first-named path, and a folding mechanism into which the web passes by the second-named path, substantially as described.
15. In a printing and folding machine, the combination of means for diverting webs from one vertical plane into another at an acute angle to the first, with printing mechanisms delivering webs into paths in the first-named plane, means for associating said webs while traveling in one of said planes, and a folding mechanism into which the associated webs pass while in the second-named plane, substantially as described.
16. In a printing and folding machine, the combination of independent means for diverting independent webs from paths in one vertical plane into paths in another vertical plane forming an acute angle with the first-named plane, with printing mechanisms, means for associating said webs after they are so diverted, and a folding mechanism, substantially as described.
17. In a printing and folding machine, the combination of means for diverting webs from one vertical plane into another at an acute angle to the first, with printing mechanisms arranged one above another in the first-named plane, means for associating said webs while they are traveling in one of said planes, and a folding mechanism into which said associated webs pass while they are traveling in said second-named plane, substantially as described.
18. In a printing and folding machine, the combination of independent means for diverting independent webs from paths in one vertical plane into paths in another vertical plane forming an acute angle with the first-named plane, with web-perfecting mechanisms arranged one above another in the first-named plane, means for associating said webs after they are so diverted, and a folding mechanism into which said associated webs pass while traveling in said second-named plane, substantially as described.
19. In a printing-machine, a register-roll, swinging arms in which the same is journaled, and pressure-rolls coacting with said register-roll and having the same axis of motion as said arms, substantially as described.
20. In a printing-machine, means for changing the course of a web from one path to another forming an acute angle with the first path, consisting of two rollers and a guide-bar, one roller being at right angles to one path and the other roller at right angles to the other path, and the guide-bar being at an angle to both rollers.
21. In a printing and folding machine, the combination of a plurality of web-perfected presses arranged one above another and having their cylinders parallel and their webs moving in the same direction, means for directing the web for the lowermost press between the printing-couple thereof farthest from the roll therefor, a folding mechanism having its longitudinal axis in a vertical plane forming an acute angle with the vertical plane in which said presses lie, and means for diverting the webs from one to the other of said planes, substantially as described.
22. In a printing and folding machine, the combination of two web-perfected presses arranged one above the other with their cylinders parallel, means for directing the web for the lower press between the members of the printing-couple farthest from the roll of paper, means for directing the web for the upper press between the members of the printing-couple nearest to the roll of paper therefor, a longitudinal folder having its axis in a vertical plane forming an acute angle with the vertical plane in which said presses lie, and independent means for diverting said webs from the first to the second vertical plane, said means each consisting of two rollers one of which is parallel with the press-cylinders and the other of which is at right angles to the folding-rolls of the folder and an angle-bar forming an angle with both said rollers and the angle-bar for the lower web being farther from the lower press than are the two rollers coacting with the lower web and the angle-bar for the upper web being nearer the upper press than are the rollers coacting with the upper web, substantially as described.
23. In a printing-machine, the combination of a web-perfected press whose cylinders are all parallel with each other, a folding mechanism having its drawing-rolls disposed at an acute angle with relation to said cylinders and a guide-roller at right angles to its said drawing-rolls, and a turning-bar located in the path of the web between the press and the folder and placed at angles with both said guide-roller and said cylinders.

Signed at New York city, in the county of New York and State of New York, this 9th day of May, A. D. 1901.
